UNITED STATES PATENT OFFICE.

JOHN A. THOMAS, OF ZANESVILLE, OHIO.

METHOD OF CHEMICALLY EXTINGUISHING FIRE.

1,164,681.

Specification of Letters Patent. Patented Dec. 21, 1915.

Application filed February 11, 1910. Serial No. 543,360.

To all whom it may concern:

Be it known that I, JOHN A. THOMAS, a citizen of the United States, residing at Zanesville, in the county of Muskingum and 5 State of Ohio, have invented certain new and useful Improvements in Methods of Chemically Extinguishing Fire, of which the following is a specification.

This invention relates to a method of 10 chemically extinguishing fire and consists of impregnating a stream under pressure, with a chemical solution from which the carbonic gas is released by the heat, after the stream reaches the fire.

15 In the accompanying drawing, I have illustrated one form of apparatus that may be employed in carrying out the invention, though it is to be understood that the result sought may be obtained in many mechanical 20 ways.

Referring to the drawing, the numeral 5 designates a water supply pipe which may be a city water supply pipe from a fire plug or may be a pipe connected to the outlet of 25 a fire engine or other source of water under pressure. This pipe leads to a water motor casing 6. The discharge pipe 7 from the casing 6 conducts the water to the fire to be extinguished. The particular form of 30 motor that is employed, is immaterial in so far as the method is concerned. The motor 6 actuates a pump 8, this pump likewise being of any desired form.

The suction 9 of the pump leads to a tank 35 10 designed to contain any concentrated solution and fire extinguishing chemical agent, which when mixed in a predetermined proportion with the water which passes through the discharge 7, chemicalizes the whole 40 stream. The discharge line 11 of the pump, leads from the pump to the main discharge 7. A valve 12 is located in the suction line 9 of the pump 8 and by means of this valve, the quantity of chemical solution delivered 45 to the stream, may be varied at will. If desired, a separate water supply pipe 14 may be employed to conduct water from the water supply pipe 5 to the tank 10. This pipe 14 has a valve 15 therein for controlling 50 the flow of water therethrough. The pur-

pose of the pipe 14 is to conduct water to the tank when preparing the concentrated solution of chemical agents.

It will therefore be seen that the present invention as a method, has a two-fold object, first, to deliver into a stream of water under pressure a predetermined quantity of fire extinguishing chemical by means of which the entire stream is chemicalized, the amount of chemical thus delivered to the stream being in a predetermined proportion and relation to the amount of water discharged, and second, to deliver to the stream of water a chemical such as bicarbonate of soda, from which the carbonic gas is released 65 only after the stream reaches the fire, the carbonic gas being released by the heat. This is an important departure from methods wherein the carbonic acid gas is released prior to the time that the stream 70 reaches the fire, for during its transit much of its fire extinguishing power is lost.

It is apparent that with elements such as herein shown and described mounted upon a wheeled fire apparatus, that many hundreds 75 of gallons of water from a city water supply may be chemicalized by means of the concentrated solution carried in the tank 10. Furthermore a tank of this character may be installed in a building and by merely 80 turning on the water supply, many hundreds of gallons of chemicalized water may be had for the extinguishing of fire.

What I claim, is—

A method of extinguishing fire with a 85 chemically impregnated stream under pressure which consists first in segregating and shunting a portion of said stream through a chemical container, and subsequently drawing the resultant solution from said 90 container by suction and positively forcing said solution into said stream by a pump driven by the main line stream under pressure.

In testimony whereof I affix my signature 95 in presence of two witnesses.

JOHN A. THOMAS.
